HEATING SYSTEM

Kemper P. Brace, South Bend, Ind., assignor to
 International Engineering Corporation, Chicago, Ill., a corporation of Illinois

Application January 14, 1938, Serial No. 184,971

8 Claims. (Cl. 200—140)

This invention relates to heating systems, and is illustrated as embodied in a domestic heating system utilizing an oil burner.

An important feature of the invention relates to a novel control system especially adapted for burners of the type in which the fuel seeps through a porous refractory element into an air stream, in that while the fuel and the air-supply are both turned on when the room temperature drops to a predetermined level, when the temperature rises again only the fuel supply is turned off, the fan continuing to operate as long as there is any fuel still burning.

Since the porous refractory member in effect stores up a substantial amount of fuel, this novel method of operation insures that it will be entirely burned before the air supply stops, thereby guarding against explosions. This method of operation also has the effect of burning off any deposits of carbon which may have formed during extended periods of operation. Preferably the circuit for this control system also includes a novel safety igniter circuit associated with the fuel-supply and fan-motor circuits.

Another feature of novelty relates to a compact and simple but reliable compound switch or equivalent control device controlled by the burner temperature for effecting the necessary changes in the igniter and fan-motor circuits to cause the above-described method of operation. The illustrated embodiment is operated by the expansion and contraction of air in a bulb or the like subject to heat produced by the burner, in such a manner as to be operated by the initial expansion or contraction of the air, so that it acts promptly. Novel means is provided for relieving excess pressures due to subsequent further expansion or contraction.

The above and other objects and features of the invention, including a novel igniter arrangement and various other novel arrangements of the parts and certain desirable mechanical constructions thereof, will be apparent from the following description of the illustrative embodiments shown in the accompanying drawings, in which:

Figure 1 is a wiring diagram of a preferred automatic control circuit;

Figure 2 is a sectional view of an alternative form of control switch for use in such a circuit; and

Figure 3 is a vertical section through a domestic steam heating boiler and furnace showing an installation of a burner with my novel control circuit.

In the arrangement illustrated in Figures 1 and 3, a suitable furnace 10 of any desired type is provided for heating a house or the like space under the control of a room thermostat 12. The bottom of the furnace 10 may be lined with fire-brick 14 or equivalent refractory material, to such height as may be necessary. An oil burner described below is mounted to discharge through a refractory shield 16 into the interior of the 10 furnace.

The burner, in the form illustrated in Figure 3, includes a generally cylindrical casing 18 having a conical end projecting through the shield 16 and open at the end opposite the furnace, for the intake of air. The casing 18 is mounted on a suitable support 20. Inside the casing there is a ledge or dam 22, forming a sump into which excess fuel drains, and directing the fuel away through a suitable drain conduit 24. This conduit may, if desired, lead to one of the standard commercial safety devices (not shown) such as a bucket switch, for opening the control circuits of the burner in case of excessive drainage of fuel therefrom.

In the open end of the casing 18, and arranged coaxially with respect thereto, suitable brackets 26 support a motor 28 provided with air-circulating means such as a fan 30 on the motor shaft. The blast of air from the fan 30 is preferably directed through a set of guide vanes 32, which are mounted in the casing 18 just beyond the fan, and which in the form shown insure a substantially straight flow of the air current and prevent spiral movement of the air. The shape and arrangement of these vanes may be suitably modified if it is desired to direct the air otherwise than in a straight path.

In the conical end of the casing 18 suitable brackets 34, riveted at their outer ends to the casing, support (coaxially of the outer casing 18) an inner casing 36. The space between the casings 18 and 36 provides an annular outer passage for secondary air from the fan 30. The inner casing 36 has in its end adjacent the fan 30 a reduced-diameter opening 38 forming an intake for primary air from the fan 30.

The oil or other fuel is supplied, for example through a conduit 40 controlled by a suitable fuel valve 42 operated by a solenoid 44, and in the 50 arrangement illustrated dripping through a feed conduit 46, to a porous refractory member 48, and seeps down through the porous structure of that member to be vaporized and taken up by the primary air.

55 The fuel need not necessarily be supplied on

the upper surface of the refractory member, as the capillary action of its porous structure will distribute the fuel satisfactorily even if it is supplied at a lower point.

The refractory member 48 may have its outlet end conical in form, so that its surface parallels the conical outlet end of the casing 18. Thus combustion of vaporized fuel and air at the base of the refractory serves to heat the tip and thereby increases the capacity of the burner.

The fuel conduit 46 discharges onto the refractory member 48, and the fuel seeps through the porous structure thereof and crosswise of the passages 62 or 64. The heat of the combustion taking place around the end of and in the passages of the refractory member vaporizes the fuel and it is taken up by the primary air. This gives unusually effective carburetion for the large volume of primary air required in a burner of this character.

The lower part of the member 48, at its outlet end, has arranged crosswise thereof a hot-wire igniter 68, connected by supporting posts 70 to the lead wires described below. This igniter is arranged in a recess formed in the refractory member, out of the direct path of the primary air, in a sort of eddy current due to the passage of the primary air. Preferably it is in direct contact with the surface of the refractory member, so that a small part of the latter is heated up to vaporize the fuel therein and bring about immediate ignition thereof in the air of the eddy current.

It will be seen that so long as fuel is supplied and the motor 28 operates, the fuel and primary air mixed in the passages 62 burns and then in turn is mixed with an outer envelope of secondary air from the annular passage between the casings 36 and 18. It will be noted that the combustion takes place immediately adjacent the refractory member, and to some extent actually in the passages 62, heating the refractory member to a high enough temperature to cause rapid vaporization of the fuel.

The burner described above, except as included in the control system hereinafter described, is claimed in my copending application No. 145,706, filed June 1, 1937.

Figure 1 shows one manner of controlling the described burner or its equivalent. A source of current, such as the secondary of a transformer 74, is connected through line wires 76 and 78, one of which contains a switch 80 operated by the room thermostat 12, to the motor 28. The switch 80 has a second contact so that it also closes a parallel circuit through wires 82 and 84 and the igniter 68. The wires 82 and 84 have connected therebetween, in parallel with the igniter 68, the fuel-valve solenoid 44. Thus closing the switch 80 closes three circuits through (1) the motor, (2) the igniter, and (3) the fuel valve solenoid.

As a safety measure, in order to shut off the fuel supply after a predetermined interval if the igniter does not operate, there is connected in shunt with the igniter a heating resistance 86 which, after the desired time interval, deflects a bimetallic strip 88, causing a plunger 90 to open a switch contact 92 in the line 82, thereby shutting off both the fuel valve and the igniter.

The wires 78 and 82 terminate in contacts 94 in an enlarged upwardly extending space 96 in a member 98 of suitable insulating material.

This member is formed with a lower horizontal passage 100 of capillary size, communicating at its ends with the space 96 and with another and somewhat higher upwardly-extending enlarged space 102 which is open to the atmosphere through a porous plug 104 held by a perforated threaded cap 106. The space 102 contains contacts 108 connected to the lines 76 and 78 around the room-thermostat switch 80.

10 The above passages form a U-shaped passage containing a globule of mercury, shown in the space 96. The mercury can pass through the passage 100 only when forced by a substantial pressure thereon. The mercury cannot pass the 15 porous plug 104, nor a similar plug 111 held by a perforated locking ring 113 leading to a passage 115 communicating with the mouth of a sealed air bulb 117.

The bulb is arranged in the path of the burned 20 gases from the burner, for example in the flue connection from the furnace as shown in Figure 1. It is not necessary that the burned gases actually impinge on the bulb, but the air in the bulb must be subject to the heat of the gases so 25 that it expands when the burner is going and contracts when it is not going.

In operation, when the room temperature drops to a predetermined level, the thermostat 12 closes the double switch contact member 80, thereby 30 closing the three circuits through the motor and the solenoid 44 and the igniter. The globule of mercury is at this time in the space 96, and completes the igniter circuit.

As soon as the burner ignites, the hot exhaust 35 gases act on the bulb 117 to expand the air therein, driving the globule of mercury through the capillary tube 100 into the space 102, thereby breaking the igniter circuit at 94 and closing the contacts 108.

40 When the room temperature rises, the contact 80 opens, breaking the circuit through the solenoid 44 and shutting off the fuel supply. A substantial amount of fuel remains in the pores of the member 48, however, so the burner is not 45 immediately extinguished. The motor circuit remains closed through contacts 108, therefore, until this fuel is all burned. Thereupon the air in the bulb 117 cools and contracts, and the atmospheric pressure in space 102 pushes the mercury globule back through the capillary passage 100 into the space 96, leaving the circuits ready 50 for the next cycle. Excess air, after the mercury has been pushed from one side to the other, merely bubbles idly through the mercury.

55 Figure 2 shows an alternative form of stack switch which has most of the advantages of the form shown in Figure 1, as well as certain other advantages. In this embodiment, the body 198 of the stack switch device contains an enlarged 60 space 196 (shown containing the mercury globule) connected by a vertically-arranged capillary U-passage 200 to a second enlarged space 202 which is at substantially constant (e. g., atmospheric) pressure.

65 The space 202 communicates by means of a passage through a pointed tip 204 (designed to prevent spilling of mercury) and through a plug 206 threaded into the wall of the switch body 198, with the interior of an auxiliary housing 208, which is not airtight and is therefore always at atmospheric pressure. This housing is shown with a removable cover 210.

The space 196, above the mercury, communicates by a passage, through a pointed tip 211

and through the lower portion of a plug or fitting 213, with a transverse opening 215 opening at one end into an air bulb 217 which corresponds to the air bulb 117 in Figure 1. The other end of the opening 215 registers with an opening 220 in the switch body 198 and thereby communicates, by means of a small passage through a stem 222 threaded into the side of the switch body, with the interior of an expandible metallic bellows 224 in the housing 208, the bellows being supported by the stem 222.

The opposite face of the bellows 224 carries a stem 226 adjustably threaded into a socket in one end of a thrust member 228 which carries, threaded adjustably thereon, spaced abutments such as nuts 230 and 232. Between these abutments is the resilient operating blade 234 of a standard commercial snap-action switch. Such a switch will be opened or closed, as the case may be, or if double-acting will be reversed in position, by the initial motion of abutment 230 or 232, but will not be operated in the reverse direction unless positively actuated in the reverse direction by the opposite abutment.

In the position shown, the blade 234 has just snapped to the right due to expansion of the air in bulb 217, where it will remain until operated by movement of abutment 232 to the left caused by contraction of the air in bulb 217. In this embodiment, the first expansion or contraction of the air operates the switch, and excess pressure thereafter is relieved by shifting of the mercury in one direction or the other through the U-passage 200, followed by passage of air through the mercury.

By utilizing a double-acting snap-action switch in this device, it can be substituted directly for the stack switch shown in Figure 1, and will operate in the same manner in the control circuit.

While one desirable control circuit, and two forms of stack switches, have been described in detail, it is not my intention to limit the scope of my invention by that description, or otherwise than by the terms of the appended claims. The present application is a partial continuation of my Patent 2,174,818 of October 3, 1939.

I claim:

1. A device for controlling circuits such as the igniter and motor circuits of a burner comprising a member having formed therein a U-passage having a central portion of capillary size such that it will not pass mercury except under substantial pressure and having enlarged upwardly-extending end portions one of which opens to atmosphere and which are closed by porous parts which will pass air but not mercury, a sealed air bulb opening into the other of said enlarged portions, a pair of circuit contacts in each of said enlarged portions and a globule of mercury normally positioned in one or the other of said enlarged portions and shifted back and forth through said capillary portion in response to variations in pressure in said bulb.

2. A device for controlling circuits such as the igniter and motor circuits of a burner comprising a member having formed therein a U-passage having a central portion of capillary size such that it will not pass mercury except under substantial pressure and having enlarged end portions one of which has means opening to atmosphere, a sealed air bulb opening into the other of said enlarged portions, a globule of mercury normally positioned in one or the other of the enlarged end portions and shifted back and

forth through said capillary portion in response to variations in pressure in said bulb, and circuit closing devices operated in response to such variations in pressure.

3. A device for controlling circuits such as the igniter and motor circuits of a burner comprising a member having formed therein a U-passage having a central portion of capillary size such that it will not pass mercury except under substantial pressure and having enlarged end portions one of which has means opening to atmosphere, a sealed air bulb opening into the other of said enlarged portions, a globule of mercury normally positioned in one or the other of the enlarged end portions and shifted back and forth through said capillary portion in response to variations in pressure in said bulb, and a pressure-operated switch connected to said bulb and opened and closed in response to such variations in pressure.

4. A device for controlling circuits such as the igniter and motor circuits of a burner comprising a member having formed therein a U-passage having a central portion of capillary size such that it will not pass mercury except under substantial pressure and having enlarged end portions one of which has means opening to atmosphere, a sealed air bulb opening into the other of said enlarged portions, a globule of mercury normally positioned in one or the other of the enlarged end portions and shifted back and forth through said capillary portion in response to variations in pressure in said bulb, and contacts in at least one of said end portions and bridged by the mercury when in said end portion.

5. A control switch comprising an air container adapted to be subjected to the temperature of part of a heating system, a device having enlarged spaces connected by a capillary passage and arranged with one space communicating with said air container and with the other space of substantially constant pressure, mercury in said device shifted back and forth through the capillary passage from one of said spaces to the other in response to variations in pressure in said air container and a switch opened and closed in response to said variations in pressure.

6. A control switch comprising an air container adapted to be subjected to the temperature of part of a heating system, a device having enlarged spaces connected by a capillary passage and arranged with one space communicating with said air container and with the other space at substantially constant pressure, mercury in said device shifted back and forth through the capillary passage from one of said spaces to the other in response to variations in pressure in said air container, and a snap action switch having means operated by an initial variation in said pressure, excess pressure due to subsequent variation in the same sense being relieved by the shifting of the mercury and the passage of air past the mercury.

7. A control switch comprising an air container adapted to be subjected to the temperature of part of a heating system, a device having enlarged spaces connected by a capillary passage and arranged with one space communicating with said air container and with the other space at substantially constant pressure, mercury in said device shifted back and forth through the capillary passage from one of said spaces to the other in response to variations in pressure in said air container, and a circuit opened or closed

by an initial variation in said pressure, excess pressure due to subsequent variation in the same sense being relieved by the passage of air past the mercury.

8. A control device comprising an air container adapted to be subjected to the temperature of part of a heating system, a device having enlarged spaces connected by a capillary passage and arranged with one space communicating

with said air container and with the other space at substantially constant pressure, mercury in said device shifted back and forth through the capillary passage from one of said spaces to the other in response to variations in pressure in said air container, and control means operated in response to said variations in pressure.

KEMPER P. BRACE.
